DOOR CHIME SIGNAL HOUSING

John G. Jolly, Cincinnati, Ohio, assignor to McTone, Inc.,
Cincinnati, Ohio, a corporation of New York

Application March 14, 1958, Serial No. 50,035

Term of patent 14 years

(Cl. D72—1)

Figure 1 is a front elevational view of a door chime signal housing, showing my new design.

Figure 2 is a side elevational view thereof.

Figure 3 is a fragmentary cross sectional view taken on the line 3—3 of Figure 1.

Figure 4 is a top plan view thereof.

Figure 5 is a cross sectional view taken on the line 5—5 of Figure 1.

Figure 6 is an enlarged fragmentary top perspective view taken from the front and right side thereof.

The side not shown is substantially identical to the side shown in Figure 2 and the bottom not shown is substantially identical to the top shown in Figure 4.

I claim:

The ornamental design for a door chime signal housing, substantially as shown and described.
